INVENTOR.

ROY A. WATKINS

BY *Carl M. Sinclair*

ATTORNEY.

UNITED STATES PATENT OFFICE.

ROY A. WATKINS, OF CLARINDA, IOWA, ASSIGNOR, BY MESNE ASSIGNMENTS, TO
EDWIN LISLE, OF CLARINDA, IOWA.

WRINGER.

1,426,526.

Specification of Letters Patent. Patented Aug. 22, 1922.

Application filed October 14, 1920. Serial No. 416,971.

To all whom it may concern:

Be it known that I, ROY A. WATKINS, a citizen of the United States of America, and resident of Clarinda, Page County, Iowa, have invented a new and useful Wringer, of which the following is a specification.

This invention relates to clothes wringers and has for its object the provision of improved means for constructing the frame 10 and facilitating assembly of the parts of the mechanism.

A further object of this invention is to provide an improved gearless wringer.

A further object of this invention is to 15 provide a swinging wringer adapted to be operated from a power shaft and having a pivot bearing of relatively large diameter.

A further object of this invention is to 20 provide an improved swinging wringer which may be set or positioned at any selected point in its orbital travel.

A further object of this invention is to 25 provide a simple, cheap and easily operated tension release mechanism for clothes wringers.

With these and other objects in view, my 30 invention consists in the construction, arrangement and combination of elements hereinafter set forth, pointed out in my claims and illustrated by the accompanying drawing, in which—

Figure 1 is an elevation, partly in section, showing my improved wringer mounted for practical use. Figure 2 is an outer end elevation of the wringer. Figure 3 is a vertical section on an enlarged scale illustrating the tension release mechanism. Figure 4 is a vertical section on the line 4—4 of Figure 5, and Figure 5 is a cross-section on the line 5—5 of Figure 4, both illustrating parts of the tension release mechanism.

Figure 6 is a cross-section similar to Figure 5 and illustrating a modified form.

In the construction of the mechanism the 45 numeral 10 designates a support of any suitable kind, which may be a portion of a washing machine. Rising from the support 10 is a bracket 11 having formed thereon a cylindrical gear case 12 open at its upper 50 end. An operating shaft 13 is suitably driven as by a motor (not shown) carried by the support 10, and said shaft is journaled in the bracket 11 and has one end projecting within the gear case 12, with a bevel 55 gear 14 fixed thereto within said case.

The wringer is formed with spaced end

bars 15, 16, a bottom bar 17 and a top bar 18, said bottom bar being formed integrally with the end bar 15. A substantially cylindrical gear housing 19 is also formed integrally with the end bar 15 and projects therefrom oppositely to the bottom bar 17. The gear housing 19 has at its lower end a reduced journal portion 20 fitting within and rotatable relative to the gear case 12, 65 whereby the wringer mechanism may be swung through an arc relative to said case and to the support. This connection provides a bearing for the wringer of large diameter and tends to hold the wringer 70 against sagging and misalignment. The wringer may be set or positioned at any point of its arcuate travel and held by means of a set screw 21 mounted through the wall of the case 12 and engaging the 75 portion 20. A shaft 22 is arranged vertically and axially in the gear housing 19 and fixed to its lower end is a bevel gear 23 meshing with the gear 14 when the wringer mechanism is in place as shown and described. Fixed to the upper end of the shaft 22, within the housing 19, is a bevel gear 24, meshing constantly with opposed bevel gears 25, 26 mounted loosely on a horizontal shaft 27 extending through said 80 housing. The shaft 27 extends within and through the wringer frame and carries one of the wringer rolls, such as 28, which contacts with a second roll 29 in a common manner. Slidably mounted on and feathered to 85 the wringer shaft 27 between the bevel gears 25, 26 is a double clutch member 30 adapted to engage selectively with clutch members formed on the opposed faces of said gears. A removable top 31 is provided for the 90 housing 19 on which is pivoted a shifting lever 32 which is extended through said top and provided with an eccentric pin 33 projecting downwardly within a circumferential groove 34 in the clutch member. 100 Movement of the lever 32 through an arc results in sliding movement of the clutch member 30 to engage it selectively with the gears 25, 26 or place it in neutral position between said gears, thus controlling the 105 rotation of the wringer shaft 27 and rolls.

Each of the end members 15, 16 of the wringer frame is formed with a vertical slot 35 (Fig. 2) within which project the ends of the top bar 18 and rolls 28, 29 and 110 also the ends of a leaf spring or tension member 36 located between said top bar and

the uppermost roll 29. The shaft 27 of the roll 28 extends through the slot of the end member 15 to the housing 19. In practice the members 18, 36, 29 and 28 are assembled 5 relative to the end member 15, in order, after which the end member 16 is so placed that the other ends of said members enter its slot 35, and it is then secured in place relative to the bottom bar 17 to hold the 10 parts in assembled position. The bottom bar 17 preferably is formed with an upwardly projecting tenon 37 at its outer end adapted to enter a notch in the lower end of the end member 16, and a pin 38 is mounted transversely through said end member and the tenon. The shaft of the roll 29 is not geared to the shaft 27 of the roll 28, but dependence is placed for driving said shaft 29 upon frictional contact of the 15 rolls, which is regulated by tension of the spring 36. The shafts of the rolls 28, 29 enter and are suitably journaled in bearing blocks 39, 40 carried by the end members 15, 16.

20 In its central portion the top bar 18 is formed with a boss 41 having a vertically arranged tapped bore into which a collar 42 is threaded. The collar 42 is formed with a vertically arranged smooth bore through 25 which extends a stem 43 having at its upper end a hand wheel 44. A clip 45 is fixed to the central portion of the spring 36 and carries on the upper side of said spring a socket 46 in which is swiveled a ball 47 30 formed on the lower end of the stem 43. Between its ends the stem 43 is formed with a longitudinal groove 48 terminating at its upper end in a laterally extending notch or 35 seat 49. A pin 50 is mounted in and radially of the collar 42, projects within the bore thereof and is adapted to travel in the groove 48 and enter the notch or seat 49 of the stem at times. The pin may be introduced to its position in the collar by 40 driving it through a radial hole 51 at the opposite side of the collar bore and through a diametrical hole 52 in the stem.

45 The lateral notch or seat 49 extends to the right of the vertical groove 48 so that 50 in use, when the stem 43 is rotated clockwise, through manual operation of the wheel 44, the lug or pin 50 finds a seat in said notch and communicates rotary movement of the stem to the collar 42; and as said 55 collar is threaded in the bore of the boss 41, such rotary movement causes also a downward movement of the collar and stem relative to said boss and applies pressure and tension to the spring 36, which overlies at its ends the uppermost bearings 40 of the wringer rolls. In this manner the desired tension and pressure is applied to the uppermost roll for the use to which it is to be put. In case it is desired to quickly 60 release the tension, as in the event a lump

65 of clothing, or the hand of the operator, becomes caught between the rolls, the wheel 44 is given a slight turn to the left, or contra-clockwise, to bring the vertical groove 48 into the plane of the pin 50, thereby 70 permitting upward movement of the stem 43 and relieving the pressure and tension on the spring 36 and uppermost roll, the pin 50 traversing the groove 48 as the stem moves upwardly. Thus an upward movement of the uppermost roll 29 is permitted 75 which is limited only by the available space in the wringer frame and the length of the groove 48, and injury to the mechanism or to objects therein is avoided. Thereafter 80 the collar 42 may be moved upwardly in the boss 41 by contra-clockwise rotary movement of the stem, to such point that the pin 50 may again enter the seat or notch 49, after which tension may again be applied 85 by rotary movement in the opposite direction.

85 In Figure 6 the groove 48^a of the stem 43^a is semi-circular in cross-section and the pin 50 is replaced by a ball 50^a seated in a 90 semi-circular depression in the wall of the bore of the collar 42^a and adapted to travel in said groove and also to find a seat in a lateral notch 49^a at the upper end of said groove. The operation and function is 95 identical with that previously described.

95 Either form provides a simple and quickly operating method of securing instant release of the tension on the wringer rolls. The pin 50 or ball 50^a forms an operative connecting member between the stem and the threaded collar when seated in the lateral notch 49 or 49^a of the latter.

100 A water board 53 is mounted beneath the lowermost roll 28 and pivoted on trunnions 105 54 entering the frame. The water board preferably is cast or molded from iron or other suitable metal.

105 I claim as my invention—

110 1. In a wringer mechanism, a frame, rolls carried by said frame, a tension member carried by said frame above said rolls, the top member of said frame being formed with a threaded bore, a collar adapted to be 115 screwed into said threaded bore and having a smooth bore, a stem extending through said bore and having at its upper end means for manually rotating it and swiveled at its lower end to said tension member, said stem being formed with a vertical groove terminating at one end in a lateral seat, and a member in said collar adapted to traverse 120 said groove and also adapted to enter said seat and form an operative connection between said stem and collar.

125 2. In a wringer mechanism, a frame, rolls carried thereby, a tension member in said frame engaging said rolls, a member threaded in said frame, a stem adapted for sliding movement in said member and engaging 130

said tension member, said stem being formed with a vertical groove having a seat extending laterally therefrom, and a connecting member in said threaded member adapted to traverse said groove and also adapted to enter said seat and form an operative connection between said stem and threaded

member and also prevent sliding movement of said stem.

Signed at Clarinda, in the county of Page 10 and State of Iowa, this 17th day of September, 1920.

ROY A. WATKINS.
